(57) **CLAIM**

The ornamental design for a point of sale apparatus, as shown and described.

DESCRIPTION

FIG. 1 is a perspective view of a point of sale apparatus showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the point of sale apparatus in state A;

FIG. 9 is a left side view of the point of sale apparatus in state A;

FIG. 10 is a perspective view of the point of sale apparatus in state B; and,

FIG. 11 is a left side view of the point of sale apparatus in state B.

The broken lines in the drawings depict portions of the point of sale apparatus that form no part of the claimed design. The unshaded areas adjacent to the solid lines form no part of the claimed design.

1 Claim, 11 Drawing Sheets
